UNITED STATES PATENT OFFICE

2,467,290

COOKING RANGE

Charles Belsky, Detroit, Mich., assignor to Avco Manufacturing Corporation, a corporation of Delaware

Application June 10, 1946, Serial No. 675,647

7 Claims. (Cl. 126—37)

1

The invention relates to gas ranges.

In gas ranges of the type in which a top burner compartment is disposed above the broiler and oven compartments, there is usually provided a top-unit which extends over the top burner compartment and carries a hinged cover for said burners when they are not in use, and a splashback. It is advantageous to provide a front panel for the top burner compartment which is integral with said top and splashback. It occasionally becomes necessary to provide access to the top burners and the gas connections and the manifold, in the top burner compartment, for inspection or repair.

One object of the invention is to provide an improved construction for removably securing the top unit, including a top-member, the splashback and front panel, which can be conveniently manipulated to provide access to the top burner compartment when it is desired or necessary.

Another object of the invention is to provide an improved construction for removably securing said top unit on the body of the range for convenient access to the burners and parts in the top burner compartment.

Other objects of the invention will appear from the detailed description.

The invention consists in the several features hereinafter set forth and more particularly defined by claims at the conclusion hereof.

In the drawings:

Fig. 1 is a perspective view of the top portion of a range to which the invention may be applied.

Fig. 2 is a sectional perspective view from the rear of the range of one end portion of the top unit in operative position on the body.

Fig. 3 is a longitudinal section taken on line 3—3 of Fig. 1.

Fig. 4 is a section taken on line 4—4 of Fig. 3.

Fig. 5 is a section taken on line 5—5 of Fig. 3, with the top unit in its operative position.

Fig. 6 is a similar view, illustrating the top unit in its raised position for providing access to the top burner compartment.

The invention is exemplified with a range of the cabinet type which comprises a sheet metal wrapper, including a horizontal top-wall 10 and a back-member 12; insulated end panels 16; a liner 18 forming a baking compartment at one side of the body and a liner 20 forming a broiler compartment at the other side of the body, the walls of which are spaced from the wrapper and end walls. The top-wall 10 of the wrapper extends between the end panels 16 and at one side

2

forms the bottom of the top-burner compartment 22.

A top unit, generally designated 23, for the range, is formed of sheet metal and comprises a horizontal top or cover member 24, an upstanding splashback 26 at the back of member 24, and a front panel 28 depending from member 24. The top unit is separate from the range-body and is movable for access to the parts disposed in the top-burner compartment 22. The unit 23 extends from end to end of the range-body. The depending front panel 28 usually carries the control handles for the gas burners in the top-burner compartment 22, which are detachable from the burners which are mounted on the range-body.

A group of gas burners 25 and the connections for supplying gas thereto are supported in any suitable manner in the burner compartment 22

on the top-member 10 of the wrapper. The horizontal member 24 of the top unit 23 is provided with an opening over the burner compartment 22 and an aeration pan 30 is supported on the margin of the opening and provided with openings for the burners 25, as well understood in the art.

15 A folding lid or cover for the burners 25 includes a leaf 32 which is hinged as at 34 to the top unit and a leaf 36 which is hinged to leaf 32, as at 38. The end is foldable against the splashback. A transverse channel bar 40 is fixedly secured,

20 usually by welding, to each end of the top-member 10 of the wrapper. The end panels 16 extend over the outer sides of said bars 40. Each channel bar 40 has a lower out-turned flange 41 which is secured to the wall 10 of the wrapper.

25 A top flange 42 underlying an inturned flange 47 on an end panel 16, and an intermediate horizontal flange which forms a transverse track-rail 43. Brackets 46, which are angular in cross-section, are secured to inturned flanges 44 on the horizontal top-member 24 of unit 23. A front roller 45 and a rear roller 47 are journaled adjacent the front and rear ends, respectively, of each bracket 46 on studs 48 which are fixed in

30 and project outwardly from vertical flanges of each bracket 46. Said rollers are adapted to travel on tracks 43 and support the top-unit 23 for fore and aft and vertically tilting movements.

35 The central portion of the top-member 24 may also be supported on fixed brackets 49.

40 The rear of top-unit 23 is adapted to be locked against vertical movement relatively to the range-body by detachable connections which are releasable by forward movement of the unit and

45 are disposed adjacent the ends of top-unit 23. Each of these connections comprises a forwardly

50

55

The rear of top-unit 23 is adapted to be locked against vertical movement relatively to the range-body by detachable connections which are releasable by forward movement of the unit and

are disposed adjacent the ends of top-unit 23. Each of these connections comprises a forwardly

55

Each of these connections comprises a forwardly

extending hook 50 which has a vertically extending portion which is fixedly mounted on the range-body, and a slot 54 in a sheet metal bracket 55 which is rigidly secured to the top-unit 23. Each hook 50 is secured by screws to a sheet metal bracket 52. Each bracket 52 comprises side-flanges provided with integral out-turned tongues 58 which are welded to members 10 and 12 of the wrapper and a connecting wall to which a hook 50 is secured. Each slot 54 is formed in a sheet metal bracket 55 which is welded to in-turned flange 57 on the top and sides of the splashback. When the top-unit 23 is in its operative position over the range-body, hooks 50 extend forwardly through the slots 54 in brackets 55 and prevent vertical separation of the top-unit 23 from the body.

A stop 60 is welded to the inner face of the lower portion of each channel bar 40, extends upwardly between the rollers 45 and 47, and is adapted to arrest the forward movement of the rear rollers 47 which are carried by brackets 46 on the top-unit 23. When the top-unit is shifted forwardly so that rear rollers 47 engage the stops 60, the front portion of top-unit 23 is free to be swung vertically and fulcrum on the axis of the rear rollers 47 and into position, as illustrated in Fig. 6, to provide access to the burners 25 and parts in the top burner compartment 22. The stops 60 are provided with curved seats 61 for rollers 47 during this tilting movement.

A strut-link 62 is pivoted, as at 63, to a lug 64 which is secured to the underside of the top-member 24 and is adapted to function as a support for securely supporting the top-unit in its raised position, as illustrated in Fig. 6, for access to the burners 25 and parts in compartment 22. A strut-link 62 may be provided adjacent each end of unit 23. A single bolt 66 is adapted to extend through a lug 67 and an inturned lower flange on panel 28 for securing the entire top-unit 23 against either forward or upward displacement and in its operative position. Bolt 66 retains the hooks 50 against release from slots 54 in brackets 55. The link 62 is foldable into a rearwardly extending position of the top-burner compartment 22 (Fig. 5).

The operation will be as follows: when the top-unit is in its operative position, it will be supported by rollers 47 and 45 on channel bars 40; hooks 50 will extend through slots 54 in brackets 55, and the single bolt 66 will lock the unit 23 against the forward or upward movement and link 62 will be folded rearwardly over the top-wall 10 of the wrapper. When access is desired to the burners 25 and other parts in the top-burner compartment 22, the bolt 66 is removed. The top-unit 23, including the splashback 26, the depending front panel 28, and lids 32, 36 are shifted forwardly, the rollers 45 and 47 travelling on tracks 43 of bars 40 until the rear rollers 47 abut against the stops 60. During the initial forward movement of unit 23, brackets 55 will release the hooks 50 on the range-body. The front of top-unit 23 will then be swung upwardly while it fulcrums on the axes of the rear rollers 47 which are held in rearwardly facing seats 61 in stops 60. The strut-links 62 will automatically swing into position to retain the unit in its raised position. A slot or dent 67 may be formed in the top-member 10 of the wrapper to hold the strut-links 62 securely in their position for retaining the unit raised. When top-unit 23 is to be replaced, strut-links 62 will be released so they will swing rearwardly with their lower ends sliding

on the wrapper, and the front of the unit will be lowered until the front rollers 45 rest on tracks 43. The entire unit is then pushed rearwardly until hooks 50 pass into slots 54 in brackets 55. The single bolt 66 may then be inserted so that the entire unit will be securely locked on the range-body.

The invention exemplifies a separate top-unit for a range, which includes a top-member, a splashback, a depending front panel which is adapted to be conveniently shifted horizontally and pivotally, for providing access to the top-burner compartment. This means is particularly advantageous where the range includes broiler and oven compartments, and a top-burner compartment, and the top-unit extends from end to end of the range-body.

The invention is not to be understood as limited to the details described, since these may be modified within the scope of the appended claims without departing from the spirit and scope of the invention.

Having thus described the invention, what I claim as new and desire to secure by Letters Patent is:

1. The combination with a cooking range including a body, a top burner compartment over the body, and a separate top unit for said compartment including a top member and an up-standing splashback rigid on the rear end of said top member, of tracks fixed on the body adjacent the ends of the compartment and extending fore-and-aft of the compartment, a pair of front and rear devices adjacent each end of the top unit and movable with the top unit and adapted to travel on the tracks for supporting the top unit horizontally while the splashback travels fore-and-aft over the compartment, and stop means on the body, engageable by the rear devices and positioned to arrest the forward movement of the top unit after the splashback has been moved forwardly over the compartment a predetermined distance, the rear devices being adapted to fulcrum on the stop means for pivotal lifting movement of the top unit, the front devices being movable off the tracks during the pivotal movement of the top unit.

2. The combination with a cooking range including a body, a top burner compartment over the body, and a separate top-unit for said compartment including a top member and an up-standing splashback rigid on the rear end of said top member, of tracks fixed on the body adjacent the ends of the compartment and extending fore-and-aft of the compartment, a pair of front and rear rollers adjacent the ends of the top-unit and movable with the top-unit and adapted to travel on the tracks and support the top-unit horizontally while the splashback travels fore-and-aft over the compartment, and stop means on the body, engageable by the rear devices, positioned to arrest the forward movement of the top-unit after the splashback has been moved forwardly over the compartment a predetermined distance, the rear rollers being adapted to engage the stop means for pivotal lifting movement of the top-unit, the front rollers being movable off the tracks during the pivotal movement of the top-unit.

3. The combination with a cooking range including a body, a top burner compartment over the body, and a separate top-unit for said compartment including a top member and an up-standing splashback rigid on the rear end of said top member, of tracks fixed on the body adj-

cent the ends of the compartment and extending fore-and-aft of the compartment, a pair of front and rear devices adjacent each end of the top-unit and movable with the top-unit to travel on the tracks for supporting the top unit horizontally while the splashback travels fore-and-aft over the compartment, stop means on the body, engageable by the rear devices and positioned to arrest the forward movement of the top unit after the splashback has been moved forwardly over the compartment a predetermined distance, the rear devices being adapted to fulcrum on the stop means for pivotal lifting movement of the top unit, the front devices being movable off the tracks during the pivotal movement of the top unit, and a strut between the body and the top-unit for holding the front of the unit raised and rear devices in engagement with the stop means.

4. The combination with a cooking range including a body, a top burner compartment over the body, and a separate top-unit for said compartment including a top member and an upstanding splashback rigid on the rear end of said top member, of tracks fixed on the body adjacent the ends of the compartment and extending fore-and-aft of the compartment, a pair of front and rear rollers adjacent the ends of the top unit and movable with the top unit and adapted to travel on the tracks and support the top unit horizontally while the splashback travels fore-and-aft over the compartment, stop means on the body engageable by the rear devices, positioned to arrest the forward movement of the top unit after the splashback has been moved forwardly over the compartment a predetermined distance, the rear rollers being adapted to engage the stop means for pivotal lifting movement of the top unit, the front rollers being movable off the tracks during the pivotal movement of the top unit, and means for locking the rear of the top unit against upward movement releasable by the forward movement of the top unit.

5. The combination with a cooking range including a body, a top burner compartment over the body, and a separate top unit for said compartment including a top member, an upstanding splashback rigid on the rear end of said top member, and a depending front fixed on the top unit for closing the front of the compartment, of tracks fixed on the body adjacent the ends of the compartment and extending fore-and-aft of the compartment, a pair of front and rear devices adjacent each end of the top unit and movable with the top unit to travel on the tracks, for supporting the top unit horizontally while the splashback travels fore-and-aft over the compartment and the front panel moves over the compartment, and stop means on the body, engageable by the rear devices and positioned to arrest the forward movement of the top unit after splashback and front panel have been moved forwardly a predetermined distance, the rear devices being adapted to engage the stop means for pivotal lifting movement of the top unit, the front devices being movable off the track during the pivotal movement of the top unit.

6. The combination with a cooking range including a body, a top burner compartment over

the body, and a separate top unit for said compartment including a top member, an upstanding splashback rigid on the rear end of said top member, and a depending front fixed on the top unit, for closing the front of the compartment, of tracks fixed on the body adjacent the ends of the compartment and extending fore-and-aft of the compartment, a pair of front and rear rollers adjacent each end of the top unit and movable with the top unit to travel on the tracks for supporting the top unit horizontally while the splashback travels fore-and-aft over the compartment with the front panel moving away from the front of the body and the splashback moving over the compartment, and stop means on the body, engageable by the rear rollers and positioned to arrest the forward movement of the top unit after splashback and front panel have been moved forwardly a predetermined distance, the rear rollers being adapted to engage the stop means for pivotal lifting movement of the top unit, the front rollers being movable off the track during the pivotal movement of the top unit.

7. The combination with a cooking range including a body, a top burner compartment over the body, and a separate top unit for said compartment including a top member, an upstanding splashback rigid on the rear end of said top member, and a depending front fixed on the top unit for closing the front of the compartment, of tracks fixed on the body adjacent the ends of the compartment and extending fore-and-aft of the compartment, a pair of front and rear devices adjacent each end of the top unit and movable with the top unit to travel on the tracks for supporting the top unit horizontally while the splashback travels fore-and-aft over the compartment and the front panel moving away from the front of the body and the splashback moves over the compartment, stop means on the body, engageable by the rear devices and positioned to arrest the forward movement of the top unit after splashback and front panel have been moved forwardly a predetermined distance, the rear devices being adapted to fulcrum on the stop means for pivotal lifting movement of the top unit, the front devices being movable off the track during the pivotal movement of the top unit, and means between the back of the body and the back of the splashback for locking the top unit against upward movement, said locking means being releasable by the forward movement of the splashback on the top unit.

CHARLES BELSKY.
